UNITED STATES PATENT OFFICE.

PAUL SCHARE, OF BERLIN, GERMANY, AND EMIL KWAYSSER, OF VIENNA, AUSTRIA-HUNGARY.

FOUR-STROKE-CYCLE ENGINE.

1,108,116.

Specification of Letters Patent. Patented Jan. 11, 1916.

Application filed February 18, 1912. Serial No. 749,219.

To all whom it may concern:

Be it known that we, PAUL SCHARE and EMIL KWAYSSER, subjects of the Emperor of Austria-Hungary, residing at Berlin, Germany, and Vienna, Austria-Hungary, respectively, have invented certain new and useful Improvements in Four-Stroke-Cycle Engines, of which the following is a specification.

Internal combustion engines in which the four working stages, namely, the suction, compression, expansion and exhaust are effected in a single crank revolution between two pistons in one cylinder are well known. From these known engines, the engine forming the subject of the present invention differs in principle by the special movements of the pistons, by the particular transmission of the piston movements to the crank, further by the use of two cylinders, and finally by its peculiar valve gear arrangement. Although, if desired, this engine could be constructed only with one cylinder, in practice owing to the special driving parts by means of which in the present case the two pistons are coupled, two cylinders have proved to be preferable to assure the desired result. The pistons of both cylinders are mutually connected with the aid of a suitable driving gear so as to effect simultaneously on the one hand the aspiration in one cylinder and the expansion in the second cylinder and, on the other hand, the compression in the first cylinder and the exhaust in the second cylinder. This arrangement and the gear used in connection therewith provide for an almost complete balance of all prevailing acceleration forces, that is to say, an entirely shockless running of the engine and also for a particularly advantageous action of the working pistons. The pistons not only perform relatively long strokes, but prior to and after attaining their common dead center positions, they travel in opposite directions at a considerable speed, whereby at the moment of the explosion and at the commencement of the expansion a high thermic effect is produced by the high speed of the pistons as they move away from one another, while at the same time the internal pressure acts simultaneously upon both of the pistons.

Although this engine with two cylinders and its gearing may be regarded as a uniform whole, it is of course obvious and also

preferable to combine several, say two, such two-cylinder engines to form a four-cylinder engine. In this case the crank shaft would receive two cranks which may be set either at an angle of 90° or at 180° according to whether importance is attached to either a more uniform momentum of rotation or to a still better balancing of the moving forces and momentums.

In the accompanying drawings: Figure 1 illustrates diagrammatically a section of an engine constructed in accordance with this invention. Figs. 2 to 9 indicate diagrammatically eight consecutive main positions of the two pistons in the right-hand cylinder, and the corresponding positions of the piston operating gear, and Figs. 10 to 12 illustrate a specific construction of the rotary valve organization preferably used in this engine. Fig. 10 is a vertical sectional view showing the cylinder, the rotary valve and the outer valve casing or distributing chamber; Fig. 11 is a horizontal sectional view of the same in the plane of the admission and exhaust slots; Fig. 12 illustrates in developed elevation a portion of the circumference of the cylinder, of the valve and of the distributing chamber; Fig. 13 is a view similar to Fig. 12, but showing a slightly modified arrangement of the ports in the cylinder, the valve and the valve casing.

As shown in Fig. 1, A and B are the two cylinders open at top and bottom and a^1, a^2 and b^1, b^2 are the two pairs of pistons working in these respective cylinders. By means of short connecting rods c^1, c^2 and d^1, d^2 the four pistons are connected to symmetrically located points g^1, g^2 and h^1, h^2 , of two bell crank levers, G and H respectively. These levers each have three connecting points g^1, g^2, m and h^1, h^2, n , with regard to which the two levers have the form of isosceles triangles, the apices m and n of which are located in the center line so as to face one another when the levers have a position of symmetry. Along the line leading from the apex to the base, the levers are provided with longitudinal slots M and N respectively by means of which, each lever has simultaneous sliding and pivotal components of movement on a stationary pivot S or T, as the case may be. The apices m and n of the two levers are each pivoted to one end of a double armed lever R which

rocks about a central stationary axis O. Rigidly attached to the lever R, at one side thereof, is an arm Q which is connected by a link P to the crank K of the main shaft F, and thereby drives said shaft.

The upper pistons a^1 and b^1 of the two cylinders are connected to the upper bell crank lever G and the lower pistons a^2 and b^2 are connected to the lower bell crank lever H.

When, in the course of the operation, the two levers G and H have a position of symmetry with respect to a common central line, all of the pivots S, m, O, n, T and F coincide with such line, as shown in Fig. 4. The levers G and H have a compound rotary and sliding movement about their respective fulcrums S and T, and in this way the point of rotation of each lever is constantly displaced along the length of its longitudinal slot.

$Z^1 Z^2$ are the spark plugs which are arranged laterally on the cylinder walls at points corresponding to the upper common dead center position of the two pistons.

The explosion on the one hand and the exhaust and suction on the other hand take place at the opposite remote ends of the cylinders, so that there is relatively small degree of temperature and pressure at the end of the cylinders through which the gases are admitted and exhausted. It is, therefore, practical to use rotary slide valves as shown in Figs. 10 to 12 and to be hereafter described in place of the ordinary conical valves. In Fig. 1 the location of the valves is suggested at u and v but the disclosure of the valves in this figure is merely diagrammatic.

In the extreme positions of the levers G and H, shown in Fig. 1 the upper piston a^1 and the lower piston b^2 at the opposite ends of the respective cylinders uncover, respectively, the explosion chamber and the terminals of the suction and exhaust passages, and in the opposite extreme positions of said levers, the pistons b^1 and b^2 have the relations just ascribed to the respective pistons a^1 and b^2 .

When the two levers G and H are in either of their extreme positions, the two cylinders are open for a greater part of their length from their relatively opposite ends, the ends of each cylinder being opened alternatively as is obvious. Thus with the parts related as in Fig. 1, the cylinder A is open for the greater part of its length from its upper end and the cylinder B is open for the greater part of its length from its lower end. When the positions of the levers G and H are reversed from those shown in Fig. 1, the cylinder A will then be open for the greater part of its length from its lower end and the cylinder B will be open for the greater part of its length from its upper

end. These relations are useful in achieving an effective direct cooling and cleaning of the cylinder interiors, owing to the surging of air into and from the open ends of the cylinders.

As is well known, in ordinary four-stroke engines it is difficult to obtain a pure air-gas mixture for the explosion, because the clearance at the exhaust or at the commencement of the suction is equal to minimum dimensions of the compression space, and therefore, a considerable quantity of burned gas is mixed with the fresh charge admitted on each suction stroke. In the improved engine, if the two fulcrums S and T are made equidistant from the axis O, the piston strokes in the upper as well as in the lower halves of the cylinders are equal and symmetrical and therefore the clearance obtained at the exhaust is exactly the same as the minimum compression space, as in the case of an ordinary four-stroke engine. But by making the distance of the upper fulcrum S from the axis O somewhat less than that of O from T, as shown in Fig. 1, the piston strokes are differentiated whereby in their upper common dead center position the pistons have a greater spacing from one another than in their lower common dead center position, thus enabling the clearance at the exhaust to be reduced at will to the smallest admissible volume irrespective of the minimum size of the compression space.

According to Fig. 1, the distance S—O is less than the distance T—O, and therefore, with the parts related as shown, the pistons in the right hand cylinder, on reaching their upper common dead center position, define a relatively large compression chamber, whereas the clearance between the pistons of the left hand cylinders, in the lower dead center positions is reduced to a minimum. After a main shaft rotation of 180° the same compression space is defined in the left hand cylinder and the same clearance at the exhaust in the right hand cylinder.

Assuming that provision is made for adjusting without interference with the running of the engine, the positions of either of the fulcrums S or T in a direction parallel to the axes of the cylinders by suitable selection of the position of one of the two fulcrums S or T, in relation to the other and to the axis O, it is possible to vary the compression within wide limits during the running of the engine, as is obvious.

Each of the two pistons in one of the cylinders traverses four dead center positions (reversing points) during one complete revolution of the crank. Twice during each crank revolution, two of these dead center positions are attained simultaneously by each two opposed pistons (Figs. 2 and

6), the position in Fig. 2 corresponding to the commencement of the suction stroke, and the position in Fig. 6 corresponding to the moment of the explosion. The position in Fig. 3 represents the absolute dead center position for the lower piston, whereas the upper piston has attained almost the maximum of its velocity. In the position shown in Fig. 4, in which the two pistons are substantially remotest from each other, the suction stroke which is started from the position shown in Fig. 2 is completed and the compression is commenced. In the position indicated in Fig. 5, the upper piston is at its absolute dead center and the lower piston approaches the upper piston at almost maximum speed. In Fig. 6 the compression is completed, both pistons being at their dead center, explosion occurs and the power stroke commences. In Fig. 7, the upper piston is at its absolute dead center and the lower piston moves away from it at almost maximum velocity. In Fig. 8, both pistons again assume their farthest position one from the other, completing the power stroke and the exhaust commences. In Fig. 9, the lower piston again assumes its dead center position. The positions in Figs. 2, 3, and 4, therefore, correspond to the suction; in Figs. 4, 5, and 6 to the compression; in Figs. 6, 7, and 8 to the expansion; and in Figs. 8, 9, and 2, to the exhaust. The dead center points of the lower piston are shown in Figs. 2, 3, 6, and 9, and the dead center positions of the upper piston occur in Figs. 2, 5, 6, and 7. The positions in Figs. 4 and 8 indicate the greatest distance of the pistons from one another.

From the above analysis of the piston movements, it will be seen that the relative stroke of the two pistons with regard to the absolute extent of movement traversed by them is great and, moreover, that the two pistons move away from one another at high speed, both from their upper (Fig. 6) and from their lower (Fig. 2) simultaneous dead center positions. These are important features of the invention, resulting in a high thermic effect, since the transmission of heat to the cylinder walls and the piston faces is reduced at the moment of explosion or at the commencement of the expansion. In a similar manner a very quick change takes place from the exhaust to the suction in the lower dead center position which is of the greatest importance, particularly owing to the use in this case of rotary valves in the place of ordinary valves. With regard to these valves, the following should be noted: As will be seen from Fig. 1, each of the two cylinders is provided with a rotary valve respectively. Each valve serves both for suction and exhaust. Of course, in the place of each of these rotary valves conical valves could be employed, but owing to the peculiar

operation of the engine, the use of the rotary valves is in this case rendered particularly important and preferable. The use of rotary valves revolving within the cylinder or surrounding the latter has been repeatedly proposed, but in ordinary four-stroke engines the valves, arranged in surrounding relation to the cylinders, are exposed to the full explosion pressure and temperature and their safe packing and lubrication can not, therefore, be attained. The position of the rotary valves in the engine described is entirely different from the known arrangements, in that the openings for the aspiration and exhaust and therefore also the corresponding controlling members must in any circumstances be arranged at the cylinder end which is remote from the explosion point. The controlling means therefore have to bear neither the compression nor the explosion pressure and the high temperature incident to the latter, and consequently, those difficulties which in four-stroke engines of the ordinary type are liable to defeat the use of such rotary valves are eliminated. In engines according to the present invention, rotary valves may be maintained in good working condition without any particular packing and lubrication.

The advantages obtained by the controlling means used in connection with this engine and specifically illustrated in Figs. 10 to 12 are as follows: First, large openings for the aspiration and the exhaust, having an area nearly four times greater than those of the usual valves; second, the radial distribution of the admission openings over the whole cylinder circumference and a shape and position of these openings which are extremely favorable for a quick and uniform charge; third, a complete balancing or relief of the valve which merely acts as a distributing element, serving to counteract suction from the exhaust conduit and, vice versa, the exhaust into the suction conduit; fourth, ready access; and fifth, the number of revolutions which amounts only to a small fraction of that of the engine.

The valve chest is separable from the cylinder, being secured by screws which provide for its ready removal, should the occasion require. The rotary valve rotates within the narrow annular space between the cylinder and valve chest, and the two required guide faces, namely, the outside of the cylinder and the inside of the outer valve chest must be suitably turned. This is provided for by the detachable relation of the valve casing. Moreover, since it is important to have a very precise position and dimension of the cylinder slots, which cannot be obtained by casting, but must be produced by machining, it is necessary for this purpose to make the valve casing detachable from the cylinder.

In Fig. 10 the cylinder is shown reversed with regard to Fig. 1, that is to say, the slots and the valve are arranged on top and the explosion point at the bottom, but this, of course, does not in any way affect the operation of the engine. The cylinder A is provided with a flange 11 to which the outer valve casing 3 is suitably attached by screws. At the level corresponding to the inlet and outlet of the gases the cylinder is provided throughout its circumference with a number of slots, each two adjacent ones of which are employed for consecutive exhaust and suction strokes. In the embodiment shown, the cylinder is provided with seven pairs of such slots, and the same number of corresponding slots is provided in the outer valve casing, while the slide valve 2 has but eight slots altogether. The distributing chamber 3 is, as shown in Fig. 11, provided with a recess 20 located co-planar with the two axes of the cylinders of the engine, this recess accommodating the driving parts of the engine during periods of their movements. The valve 2 carries at its upper end a pinion 6 actuated by suitable gearing from the crank shaft. The valve casing 3 includes three annular superposed divisions or chambers. These three chambers may be combined either in a single casting, or, to reduce the cost of manufacture, they may be formed in two or three separate parts, which are securely fitted to one another. The intermediate division or chamber of the valve casing is of generally triangular cross section, being divided by partitions into a number of separate compartments 17 and 18. In the example illustrated, seven pairs of slots are employed, and the valve casing chamber aforesaid is provided with fourteen such compartments. The other two divisions or chambers of the valve casing 3 are located above and below the said compartments. Of these two chambers, one, as 4, serves for the admission and the other, as 5, for the exhaust. These last two chambers communicate by sockets 15 and 16 with the carburetor and the exhaust conduit respectively. Of the compartments above referred to, those designated 17 communicate by way of passages 10 in the lower oblique wall (Fig. 11) with the suction chamber 4, and those designated 18 and arranged alternately with reference to the compartments 17 communicate by passages 9 in the upper oblique wall (Fig. 10) with the exhaust cavity 5. Each compartment terminates at the cylindrical inner wall of the casing 3 in a slotted opening, the slots for the compartments 17 being shown at 12, and those for the compartments 18 at 13. The valve is assumed to rotate in a counter-clockwise direction, having one revolution to every eight of the crank shaft and during its rotation its slots 14 consecutively and

alternately connect the cylinder slots 7 and 8 with the slots 12 and 13 of the respective compartments 17 and 18, thereby alternately putting the suction and exhaust conduits into communication with the cylinder.

Fig. 13 shows an arrangement of inlet, exhaust, and valve slots which may be employed instead of the arrangement shown in Fig. 12, and which has the advantage of utilizing the maximum port areas available for the purposes in view. According to the construction shown in Fig. 13, the slots 7 and 8 in the cylinder wall of the valve casing are of the same width as the intervening webs of material by which said respective slots are separated from one another. The utilization of the slot arrangement shown in Fig. 13 is rendered possible in connection with the engine described, by reason of the fact that the space between the two pistons of each cylinder is, during the compression and power strokes of said pistons, wholly at one side of the zone in which the slots 7 and 8 are located (Figs. 5 to 8) and hence, out of communication with said slots. It follows that the uncovering of said slots by the rotating valve during said compression and power strokes is without effect. The slots 14 in the rotating valve are, of course, equal in size to the slots 7, 8, 12, and 13.

Having fully described our invention, we claim:

1. In a four-cycle internal combustion engine, a cylinder, a pair of opposed pistons therein, a main shaft, a two-armed rocking lever connected to the main shaft to effect the rotation thereof, and connections between one arm of said lever and one of said pistons and between the other arm of said lever and the other piston, the connections including a pair of levers pivotally connected to the opposite arms of said first named lever and each having pivotal and sliding components of movement and a rod connecting said last named lever and the respective pistons.

2. In a four-cycle internal combustion engine, a pair of parallel cylinders, a pair of opposed pistons working in each cylinder, a main shaft, a two-armed rocking lever connected to the main shaft to effect the rotation thereof, and operative connections between the pistons at corresponding ends of said cylinders and one arm of said lever and between the other pistons and the other arm of said lever.

3. In a four-cycle internal combustion engine, a pair of parallel cylinders, a pair of opposed pistons working in each cylinder, a main shaft, a two-armed rocking lever connected to the main shaft to effect the rotation thereof, and operative connections between the pistons at corresponding ends of said cylinders and one arm of said lever and between the other pistons and the other arm

of said lever, the connections comprising a pair of levers pivoted to the respective arms of said first named lever and having pivotal and sliding components of movement and 5 rods connecting each of the levers of said pair with the pistons at the ends of the cylinders which said levers adjoin.

4. In a four-cycle internal combustion engine, a cylinder, a pair of opposed pistons 10 therein, a main shaft, a two-armed rocking lever connected to the main shaft to effect the rotation thereof and connections between one arm of said lever and one of said pistons and between the other arm of said 15 lever and the other piston, the connections including a pair of levers pivotally connected to the opposite arms of said first named lever and each having pivotal and sliding components of movement and rods connecting 20 said last named levers and the respective pistons, the pivotal axes of the levers of said pair being located at different distances from the pivotal axis of said rocking lever.

5. In a four-cycle internal combustion engine, a cylinder, a pair of opposed pistons 25 therein, a main shaft, each piston having four dead center positions during a revolution of said shaft and said pistons having two of their dead center positions simultaneously and moving oppositely to one another at nearly equal speed shortly before and shortly after reaching their said simultaneous dead center positions, each piston attaining nearly its greatest speed during the 30 other dead center position of the other piston, a two-armed rocking lever connected to the main shaft to effect the rotation thereof, and connections between the arms of said lever and the respective pistons to cause 35 the operations of the latter in the sequence stated.

6. In a four-cycle internal combustion engine, a pair of parallel cylinders, a pair of opposed pistons working in each cylinder, a 40 main shaft, a two-armed rocking lever connected to the main shaft to effect the rotation thereof, and operative connections between the arms of said lever and said pistons whereby the pistons of one cylinder 45 have their power and exhaust strokes simultaneously with the respective suction and compression strokes of the pistons of the other cylinder.

7. In a four-cycle internal combustion engine, a pair of parallel cylinders, a pair of opposed pistons working in each cylinder, a main shaft, a two-armed rocking lever connected to the main shaft to effect the rotation thereof, and operative connections between 50 the pistons at corresponding ends of said cylinders and one arm of said lever and between the other pistons and the other arm of said lever, the connections comprising a pair of double bell crank levers pivoted at 55 their apices to the respective arms of said

rocking lever and rods connecting each bell crank lever with the pistons at the corresponding end of the engine.

8. In a four-cycle internal combustion engine, a pair of parallel cylinders, a pair of opposed pistons working in each cylinder, a main shaft, a two-armed rocking lever connected to the main shaft to effect the rotation thereof, and operative connections between the pistons at corresponding ends of 70 said cylinders and one arm of said lever and between the other pistons and the other arm of said lever, the connections comprising a pair of double bell crank levers pivoted at their apices to the respective arms of said 75 rocking lever and each having a longitudinal slot in line with said apices, fixed fulcrum pins engaged in said slots and rods connecting each bell crank lever at opposite sides of its apex with the pistons at the corresponding end of the engine.

9. In a four-cycle internal combustion engine, a pair of parallel cylinders, a pair of opposed pistons working in each cylinder, a main shaft, a two-armed rocking lever 90 connected to the main shaft to effect the rotation thereof, and operative connections between the pistons at corresponding ends of said cylinders and one arm of said lever and between the other pistons and the other arm of said lever, the connections comprising a pair of double bell crank levers pivoted at their apices to the respective arms of said 95 rocking lever and each having a longitudinal slot in line with said apices, fixed fulcrum pins engaged in said slots and rods connecting each bell crank lever at opposite sides of its apex with the pistons at the corresponding end of the engine, said fulcrum pins 100 being located at different distances from the 105 axis of said rocking lever.

10. In a four-cycle internal combustion engine, a cylinder, a pair of opposed pistons therein, a main shaft, a two-armed rocking lever connected to the main shaft to effect 110 the rotation thereof, connections between one arm of said lever and one of said pistons and between the other arm of said lever and the other piston, the cylinder having openings for the admission and exhaust, a distributing casing surrounding the cylinder, and an unpacked rotary valve surrounding the cylinder and controlling said openings, the valve being located in the annular space 115 between the cylinder and said distributing casing.

11. In a four-cycle internal combustion engine, a cylinder, a pair of opposed pistons therein, a main shaft, a two-armed rocking lever connected to the main shaft to effect 120 the rotation thereof, connections between one arm of said lever and one of said pistons and between the other arm of said lever and the other piston, the cylinder having openings for the admission and exhaust, a dis- 125 tributing casing surrounding the cylinder, and an unpacked rotary valve surrounding the cylinder and controlling said openings, the valve being located in the annular space 130

tributing casing surrounding the cylinder and detachably connected thereto, and an unpacked rotary valve surrounding the cylinder and controlling said openings, the 5 valve being located in the annular space between the cylinder and said distributing casing.

12. In a four-cycle internal combustion engine, a cylinder, a pair of opposed pistons 10 therein, a main shaft, a two-armed rocking lever connected to the main shaft to effect the rotation thereof, connections between one arm of said lever and one of said pistons and between the other arm of said lever and the other piston, the cylinder having openings for the admission and exhaust and arranged in pairs, a distributing casing surrounding the cylinder and having three superposed annular chambers, the intermediate one of which is divided into compartments, each terminating in a slot at the inner circumferential face of said casing, 15 said slots coinciding with said openings and said compartments communicating in alternation with the other chambers, and an unpacked rotary valve surrounding the cylinder and controlling the communication of said openings and said slots, said valve being 20 25

located in the annular space between said cylinder and said distributing casing and 30 having one opening for each pair of openings in said cylinder.

13. In a four-cycle internal combustion engine, a pair of parallel cylinders, a pair of opposed pistons working in each cylinder, 35 a main shaft, a two-armed rocking lever connected to the main shaft to effect the rotation thereof, and operative connections between the pistons at corresponding ends of said cylinders and one arm of said lever and 40 between the other pistons and the other arm of said lever, said connections being selected whereby when the pistons of either cylinder are in their extreme inward position, the explosion chamber of one cylinder and the 45 suction and exhaust openings of the other cylinder are simultaneously and completely uncovered.

In testimony whereof we have hereunto set our hands in presence of two subscribing 50 witnesses.

PAUL SCHARF.
EMIL KWAYSSER.
